United States Patent

Des. 242,284

Patented Nov. 9, 1976

242,284

ABSORBENT TOWELING FABRIC OR SIMILAR ARTICLE

Arthur Herbert Drelich, Plainfield, N.J., assignor to Johnson & Johnson, New Brunswick, N.J.

Filed Nov. 6, 1974, Ser. No. 521,301

Term of patent 14 years

Int. Cl. D5—06

U.S. Cl. D59—2 B

FIG. 1.

FIG. 2.

FIG. 1 is a plan view of an absorbent toweling fabric or similar article showing my new design; and
FIG. 2 is an end view thereof.

I claim:
The ornamental design for an absorbent toweling fabric or similar article, as shown.
